UNITED STATES PATENT OFFICE.

JOSEPH T. WEBBER, OF BALTIMORE, MARYLAND, ASSIGNOR TO MAY OIL BURNER CORPORATION, OF BALTIMORE, MARYLAND, A CORPORATION OF MARYLAND.

LIQUID-FUEL-FEEDING DEVICE.

Application filed March 15, 1927. Serial No. 175,802.

The present invention relates to improvements in liquid fuel feeding devices, especially a valve means adapted to be used in connection with force feed oil burners.

Among the objects of the invention is to provide a simple and durable construction by which the supply of oil to a burner will be positively and automatically cut off when from any cause the pressure of the force pump ceases or falls below a predetermined amount.

The embodiments of the invention herein-after particularly described are relatively cheap of manufacture and include a minimum number of parts which may be readily renewed as desired.

In the accompanying drawing,

Figure 1 is a vertical longitudinal section through a valve constructed in accordance with the present invention.

Figure 2 is a horizontal view, substantially on the line 2—2 of Figure 1.

Figure 3 is a vertical longitudinal section of a slightly different embodiment of the invention.

Figure 4 is a section on the line 4—4 of Figure 3.

Referring to the drawing in the several views of which corresponding parts are designated by like reference characters, the body of the improved device includes a casing 1 which is provided at its lower end with an inlet or supply opening 2. As shown, the lower end of the casing is reduced somewhat in diameter and provided with a suitable thread 3 by means of which the inlet port 2 may be connected with a suitable pipe or conduit leading from the outlet of a pump, not shown.

The casing is provided with a tubular boss which, as shown, extends, both inwardly and outwardly, laterally from the body thereof, the inner end of the bore 5 of such member being directed upward and terminating in a tapered valve seat in substantial alignment with the axis of the inlet port 2.

The outwardly projecting portion of said boss is provided with a thread 6 by means of which it may be connected to a suitable conduit leading to a burner, not shown.

An outlet 7 is provided in the side wall of the casing 1 at a point above the plane of the adjacent valve seat, and as shown, this communicates with the interiorly threaded bore

of a boss 8 that is intended to receive one end of a by-pass conduit, by means of which any fuel not delivered to the burner, may be returned to a suitable container or storage tank as is commonly done in apparatus of the character for use in which the present improvements are particularly designed.

The parts so far described can be formed as a single casting, thus reducing the cost of manufacture, and providing a very strong and durable construction.

As shown in Figure 1, the upper end of the casing 1 is closed by a plug 10 having threaded engagement with the side wall of the casing, and a cap 11 is fitted over this plug and the adjusting screw 12 by means of which the force of a main spring acting to normally maintain the valve closed, hereinafter more particularly described, may be varied.

A passage or duct 13 formed in the side wall of the casing 1 connects the by-pass outlet 7 with upper portion of the interior of the casing.

Referring particularly to Figures 1 and 2, the upper wall of the tubular member before referred to for supplying oil to the burner, extends entirely across the interior of the casing, and is provided with a plurality of passages 15 through which liquid fuel supplied by a pump to the inlet port 2 may pass. In this embodiment of the invention the upper inner end of the bore 5 extends slightly above the plane of the body of said member and about the adjacent valve seat is formed an exteriorly threaded boss 16. A cap 17 is engaged with the threads on this boss 16 and through the side wall of such cap are formed a plurality of passages or perforations 18 through which the liquid fuel may flow to the bore 5 when the valve 20 is raised from its seat.

As shown in Figure 1, the valve is in the form of an elongated stem having its lower end of substantially conical form corresponding to and adapted to fit snugly against the adjacent valve seat. The valve 20 extends outwardly through the cap 17 and within the chamber in the latter is provided with an annular flange 21. A coil spring 23 interposed between said flange 21 and the end of the member in which the valve seat is formed, acts to raise said valve and permit the flow of liquid fuel from the

inlet port 2 and passages 15, 18 into the bore 5 which, as before described, communicates with the burner supply pipe.

In order that the valve may only be opened 5 when there is a sufficient pressure of liquid fuel or when the pump is acting, means are provided for counteracting the effect of the coil spring 23 and holding the valve closed.

As shown, such means include a piston 25 10 fitted within the casing 1 and having a depending skirt 26 in which are formed apertures 27 adapted to communicate with the by-pass outlet port 7, and a channel 30 communicating therewith and formed in the inner face of the side wall of the casing 1, when said piston is raised sufficiently by the pressure of fluid beneath it.

A spring 40 seated in a recess in the upper 20 end of the piston body and surmounted by a disc 41 with which the adjusting screw 12 engages, acts to normally hold the parts in the position shown in Figure 1 in which the piston bears upon the upper end of the valve 20 and maintains the same, against the open 25 position of the relatively light spring 23, in close contact with the valve seat.

It will be seen that when the pump connected with the inlet port 2 is operating and the pressure thereby created beneath the piston 25 is sufficient the latter will be moved upward, thus releasing the valve 20 from the pressure of the spring 40. As soon as this pressure is removed, the spring 23 will lift the valve from its seat and thereafter the liquid fuel will flow through the perforations 18 into the bore 5 and therefrom to the burner tube conduit. If the amount of fluid being pumped at any time becomes excessive, the piston 25 will be raised higher and the ports 27 brought into communication with the by-pass outlet 7 so that the excess fluid will be conveyed through such outlet and by-pass to a suitable receptacle.

As soon as the pump stops, from any cause, 45 or the pressure created thereby falls below that of the spring 40, the valve 20 will be forced into close contact with its seat and communication between the casing 1 and the burner conduit positively cut off.

50 In the slightly different embodiment of the invention illustrated in Figures 3 and 4, the outwardly projecting portion of the boss in which the burner supply bore 5 is provided has an enlarged interiorly threaded recess 50 adapted to be engaged with a suitable thread on the burner supply conduit.

60 In this embodiment of the invention the valve is of a slightly different form from that previously described. The body 51 of the piston is provided with a reduced depending stem 52, the lower end of which is further reduced to provide a tapered portion 53 that conforms to and is adapted to fit closely against the valve seat provided 65 at the inner end of the bore 5.

As shown, the body of the piston 51 is of slightly less diameter than the casing 1 so that the by-pass outlet 7 is constantly in communication with the lower portion of the chamber within the casing.

In this embodiment of the invention, the piston is guided in its vertical movement by a web 54 through which is formed a port 55 that connects the by-pass outlet 7 with the interior of the casing above said web 54.

The upper end of the piston body 51 is provided with a cavity into which projects the lower portion of a piston rod 60. As shown, the wall of the cavity in the end of the piston is of cup-shape form and the free face of the head 61 at the lower end of said rod is of such form that it makes an annular contact with the bottom of the cavity so that there may be relative lateral movement between the rod and piston body to insure that the valve will be accurately seated when desired.

The connection between the rod 60 and piston body 51 includes a sleeve nut 62 which is engaged with a thread in the inner face of the wall of the cavity at the upper end of the piston body, and extends over an annular flange 64 on the head at the lower end of the rod 60. The outer end of the piston rod 60 is guided in an adjustable plug 65 which engages the end wall of a closure 66 for the outer end of the casing 1. A coil spring 67 arranged between washers 68, 69, respectively bearing upon the piston rod head 63 and resting on said spring, acts to normally maintain the valve 53 in closed relation to the valve seat, but when the pressure of fluid in the lower portion of the casing 1 is sufficient to lift the piston 51 against the action of said spring, the valve will be raised from its seat and the fluid can flow outward to the burner through the bore 5 as previously described.

65 A cap 70 is provided for enclosing the projecting end of the adjusting screw and piston stem guide 65.

70 It is believed that the operation and advantages of the invention will be readily appreciated from the foregoing description in connection with the drawing.

75 It will be seen that the entire device is of very simple construction including a minimum of parts which are relatively cheap to manufacture, and are so assembled that any one or more of them can be readily removed and replaced if necessary.

Having thus described my invention, what I claim is:

1. A liquid fuel feeding device comprising 80 a casing having an inlet port at its lower end, a tubular member extending laterally into the casing and having the inner end of its bore directed upward, in substantial alignment with the axis of the casing inlet, and forming a tapered valve seat, a by-

pass outlet being provided in the side wall of the casing at a point above the plane of said valve seat, a valve having a tapered lower end extending into and cooperating with said valve seat, a coiled spring within the casing acting to maintain the valve in contact with the seat to prevent the flow of liquid fuel outward through the bore in said boss, and means controlled by the pressure of liquid in the casing for lifting the valve from its seat.

2. A liquid fuel feeding device comprising a casing having an inlet or supply port at its lower end, adapted to be connected with a pump outlet, and provided above said inlet with an inwardly projecting, integral tubular boss, the inner end of the bore in said boss being directed upward in substantial alignment with the axis of the casing inlet and forming a tapered valve seat, a bypass outlet being provided in the side wall of the casing at a point above the plane of said valve seat, a valve having a tapered lower end extending into and cooperating with said valve seat, a coiled spring within the casing acting to maintain the valve in contact with the seat to prevent the flow of liquid fuel outward through the bore in said boss, and means controlled by the pressure of liquid in the casing for lifting the valve from its seat.

3. A liquid fuel feeding device comprising a casing having an inlet or supply port at its lower end, adapted to be connected with a pump outlet, and provided above said inlet with a tubular boss extending laterally into and exteriorly of the casing, the portion of said member extending outward from the casing being threaded for connection with a suitable burner conduit and the inner end of the bore in said boss being directed upward in substantial alignment with the axis of the casing inlet and forming a tapered valve seat, a second tubular boss being provided on the casing above the plane of said seat and having a thread whereby it may be connected with a by-pass conduit, a valve having a tapered lower end extending into and cooperating with said valve seat, a coiled spring within the casing acting to maintain the valve in contact with the seat

to prevent the flow of liquid fuel outward through the bore in said boss, and means controlled by the pressure of liquid in the casing for lifting the valve from its seat. 55

4. A liquid fuel feeding device comprising a casing having an inlet or supply port at its lower end adapted to be connected with a pump outlet, and provided above said inlet with an inwardly projecting tubular member, the inner end of the bore in said member being directed upward in substantial alignment with the axis of the casing inlet and forming a tapered valve seat, a bypass outlet being formed in the casing wall, a piston within the casing having a depending valve adapted to cooperate with said valve seat, a rod connected with the body of the piston by a joint permitting relative lateral movement between said parts, to insure accurate contact between the valve and seat, and a coiled spring surrounding the piston rod and acting to normally retain the valve against the seat. 65 70

5. A liquid fuel feeding device comprising a casing having an inlet or supply port at its lower end adapted to be connected with a pump outlet, and provided above said inlet with an inwardly projecting tubular member, the inner end of the bore in said member being directed upward in substantial alignment with the axis of the casing inlet and forming a tapered valve seat, a piston within the casing having a depending valve adapted to cooperate with the valve seat and having a cavity in its upper end the bottom wall of which is of tapering form and the annular wall of which is provided with a thread, a piston rod having its lower end extending into said cavity in the body of the piston and contacting with the bottom thereof to permit relative lateral movement between the piston body and said rod, an abutment being provided on the rod within said cavity, a nut engaging the thread in said cavity in the piston and positioned over said abutment, and a spring acting to exert pressure on the piston to normally retain the valve against the seat. 85 90 95

In testimony whereof I have hereunto set my hand. 100

JOSEPH T. WEBBER.
